UNITED STATES PATENT OFFICE.

EDWARD A. LANGENBACH, OF CANTON, OHIO.

DESIGN FOR A CEILING-PLATE.

SPECIFICATION forming part of Design No. 26,238, dated November 3, 1896.

Application filed September 23, 1896. Serial No. 606,782. Term of patent 7 years.

To all whom it may concern:

Be it known that I, EDWARD A. LANGENBACH, a citizen of the United States, and a resident of Canton, county of Stark, State of Ohio, have invented and produced a new and useful Design for Metallic Ceiling-Plates, of which the following is a full, clear, and exact description, reference being had to the accompanying drawing, making part of this specification.

The invention relates to a new design for metallic ceiling-plates; and it consists of a plate of the ornamentation and form shown in the accompanying drawing, in which the design is illustrated in a plan view.

The leading feature of the design is a plate rectangular in outline and provided with ornamental circles 1, consisting of concentric double lines 2 and 3, between which are minute circles 4. Within each circle 1 is a four-sided figure 5, the sides of which are curved inward toward the center and which are formed of double parallel lines 6, inclosing minute circles 7. Within the four-sided

figure and central thereto is a rosette 8, from which radiate leaf-shaped figures 9, and adjacent to the outer ends of said figures 9 are angular figures 10, each pair of which inclose a circular figure. At the center of the plate and at other points where each four circles meet are rosettes 12, from which radiate four ribs 13, between which are irregular lines or blades 14, and between the circles 1 and the curved circles of the four-sided figure 5 are scrolls or ornamental figures 15.

The general effect of the design is that of a series of ornamental circles cutting each other, and the several accessories make a very pleasing design.

What I claim is—

The design for a metallic ceiling-plate, as herein shown and described.

In testimony whereof I have hereunto set my hand this 30th day of July, A. D. 1896.

EDWARD A. LANGENBACH.
